UNITED STATES PATENT OFFICE.

BENJAMIN COHEN, OF NEW YORK, N. Y.

DESIGN FOR A RUG.

42,685.

Specification for Design.

Patented July 2, 1912.

Application filed May 10, 1912. Serial No. 696,507. Term of patent 3½ years.

To all whom it may concern:

Be it known that I, BENJAMIN COHEN, a citizen of the United States, residing at the borough of the Bronx, city of New York, county of New York, and State of New York, have invented a certain new, original, and ornamental Design for Rugs, of which the following is a specification, reference being had therein to the accompanying drawings, forming part thereof.

The figure is a plan view of a quarter-section of a complete rug, showing my new design.

I claim:

The ornamental design for a rug, as shown.

BENJAMIN COHEN.
